MATCH BOOKLET

William Lang, McKeesport, Pa.

Application December 4, 1940, Serial No. 368,488

15 Claims. (Cl. 206—29)

This invention relates to match booklets and particularly to that type of match booklets which contain pull-matches, which matches ignite while being pulled out of the booklet.

The invention consists of a band of thick paper, cardboard or other appropriate pliable and inflammable material of desirable dimensions, the end portions of which are divided into a series of strips somewhat longer than the intended match. At a suitable place along each of the strips, depending on the desired length of the matches, an ignitable material is provided. Another part of the band is coated with a suitable igniting composition and the band is folded transversely so that a booklet is formed in which the tipped ends of the strips which form the match heads or match tips are inside the booklet and the outer or gripping ends protrude. The ignitable material and the igniting composition are so disposed that a match while being withdrawn from the booklet will cause the ignitable match end to frictionally engage the igniting composition and ignite the match. The inner portion of the strip will be drawn into the space formerly occupied by the match portion and close it so as to prevent any stray sparks from travelling down through the channel between adjoining matches vacated by the match, and thus ignite the remaining match heads.

It is one of the objects of this invention to provide a booklet with pull-matches, which is safe to manipulate and inexpensive to manufacture.

A further object of the invention is to provide a simple and effective form of match-booklet in which the booklet and the matches are integrally made of one piece of a suitable material.

A still further object of the invention is to provide a booklet which may be manufactured in continuous operation from a band or strip of pliable, inflammable material such as cardboard or the like.

In the accompanying drawings, in which like numerals represent like parts in the related views, I have shown for purposes of illustration only, certain preferred embodiments of my invention.

In the drawing:

Figure 1 is a view of a part of a band from which a match booklet is made according to my invention.

Figure 2 is a perspective view of the band folded and prior to stapling.

Figure 3 is a cross section of a booklet made from the band shown in Figure 1.

Figure 4 is a cross sectional view similar to Fig. 55

ure 3, but just after a match has been withdrawn. Figure 5 is an end view of a booklet shown after stapling.

Figure 6 is a perspective view of a modified booklet prior to stapling.

Figure 7 is a cross section of another modified form of booklet.

Figure 8 is a cross section of still another modified form of booklet,

10 Figure 9 is an enlarged view of a modified detail,

Figure 10 is a cross-section of the detail shown in Figure 9,

15 Figure 11 is an enlarged view of still another modified detail,

Figure 12 is a cross section of the detail shown in Figure 11,

Figure 13 is a view of a detail showing a modified match end, and

20 Figure 14 is a view corresponding to Figure 5, showing still another modification of the match booklet.

In the drawing, there is shown in Figure 1, a band or strip 19 of a pliable and inflammable material as for instance cardboard from which the match booklet is made. The band is subdivided by transverse fold creases 11, 12, 13, and 14 and transverse bend crease 15 into a plurality of sections, namely, match sections 16 and 21, inner flaps 17 and 20, and cover sections 18 and 19. Both ends of the band are slit longitudinally along the lines 22 into match strips 23 and side tabs 24. The slits extend through sections 16 and 21, and to the point 25 in the adjoining inner flap sections 17 and 20, respectively. The strips 23 are longer than the desired matches and are perforated or otherwise weakened along the tear line or weakened zone 26, so that each strip is frangibly divided into two portions, the outer portion constituting a match element, which may be readily detached from the stub or inner portion, which extends from the tear line 26 to the point 25.

45 Suitable ignitable material 27 is secured to each match closely adjacent the tear line 26, the portion of the match to which the ignitable material is attached is herein referred to as the "ignitable portions." Disposed on the inner flap 17, closely adjacent the fold line 12 and on the 50 same surface of the band as the ignitable material is secured, is a match igniting surface 28, preferably in the shape of a transverse ribbon, which extends on each side at least as far as the outer edges of the outside matches. So also the inner flap 20 has secured thereto a similar

igniting surface 29, disposed closely adjacent the fold line 13.

The booklet is made by folding the band 10 along the fold lines 11, and 14 so that the upper faces (those shown in Figure 1) of the match sections 16 and 21 will lie along the upper faces of the inner flaps 17 and 20, respectively, and the lower faces of the inner flaps 17 and 20 will be against the lower faces of the cover sections 18 and 19 respectively. Then, by bending the band around the bend crease 15 so that the upper faces of sections 18 and 19 turn away from each other, the booklet will assume the shape shown in Figure 2. The matches 23 are disposed in two face to face rows, but with the ignitable heads well within the folds and facing in opposite directions and towards the igniting surfaces 28 and 29 respectively. After folding the band, the staples 30 (shown in Figure 2 in the act of being applied) are passed through the edges of the various sections or folds and clinched. The booklet could of course be held in final shape, by other means than stapling, such as for example, by pasting the edges of the sections together or by banding.

The various parts are so proportioned that they assume, when folded into a booklet, the relative positions indicated in the drawing. A typical arrangement is that shown in section in Figure 3 in which the upper surfaces of cover sections 18 and 19 form the outside of the covers of the booklet, the sections 17 and 20 form the inner flaps, and the sections 16 and 21 form the center flaps or match sections. The relative lengths of the sections are such that the ends of the strips 23 project above the open end of the booklet to form gripping tabs or pull tabs. The side tabs 24 are shorter than the match strips 23 and terminate at or below the fold lines 12 and 13. If desired, the side tabs 24 may be longer or shorter than illustrated. The strips 23 are of such a length that when they are pulled out of the booklet to the tearing off position, (shown in Figure 4) the tear line 26 is adjacent to the top of the fold 13, or fold 12 as the case may be. In the tearing off position the stub end of strip 23 remains attached to the section 17 and has been moved from the position shown on the right side of Figure 3 to the position shown on the right side of Figure 4, where the stub fills up the space between adjoining strips 23, which was vacated by the pulled out match. Closing up the vacated space prevents a stray spark from the igniting match from travelling backward to the match heads remaining in the booklet.

The booklet shown in Figure 6 is similar to the one shown in Figures 1 and 2 except that the tab 24', through which a staple 30' is passed, is placed at a position between the matches, here shown in the middle of the booklet. This arrangement is slightly more economical than that shown in Figures 1 and 2, in that only one staple is used and two extra matches provided.

In the modification shown in section in Figure 7 the ignitable material 27a is provided on both sides of the matches disposed in a single row. Two igniting surfaces 28a and 29a are provided. If desired, the matches shown in the previously described embodiments could likewise have ignitable material on both sides of the head.

The modification shown in Figure 8 is similar to that shown in Figure 7, except that the cover 18b is extended and bent to form a closing flap 32 which extends over the ends of the matches

23b. The end of the flap is folded into the slot 33 in the cover 19b.

In Figures 9 and 10, I show a modification of the match end which presents a greater contact area between the ignitable material 27c and the match. By making a hole 34 in the match strip 23c near the tear line 26c, the ignitable material 27c will be caused to flow around and through the hole and cover an area around the hole on both surfaces of the match. This construction secures the ignitable material more firmly in place, and presents a greater area of match end to the igniting flame.

In the modification of the match end shown in Figures 11 and 12, there is provided two notches 36 and 37 which extend into opposite edges of the match strips adjacent the tear line 26d. The ignitable composition surrounds the neck portion lying between the notches. The ignitable material is locked into place and a large area of the match is exposed to the igniting flame. The exposed area of ignitable material is also greater than that shown in Figure 1.

In Figure 13 I present a modification of the pull tabs of the match strips. The tab or outer end 38 of each match strip is tapered to provide a convenient match separating and gripping arrangement.

It is obvious that either of the constructions shown in Figures 9 and 10 or in Figures 11 and 12 could be used in place of the match head construction shown in Figure 1. The match end construction shown in Figure 13 could be used in connection with either of the constructions of the match head shown in Figures 1, 9, and 11.

In Figure 14 there is shown a modification of the booklet of which the structure is quite similar to that illustrated in Figures 1 through 5, but with the addition of guard flaps 39, which flaps project beyond the fold lines 12e and 13e. The flaps are formed by portions 40 and 41 which are slitted from the cover sections 18 and 19 respectively, along the dotted lines shown in Figure 1. In the booklet the flaps extend upwardly from the fold lines 12e and 13e. These guard flaps serve to prevent unintentional withdrawal of the matches when the booklet is being removed from a container such as the user's pocket.

The embodiments of my invention which I have shown and described are economical to manufacture, convenient to use, and provide unusual safety features.

While I have described certain preferred embodiments of my invention, it will be understood that various changes may be resorted to and the invention otherwise embodied within the scope of the following claims.

I claim:

1. A match booklet comprising an integral strip having an end portion slitted to form a plurality of detachable match elements, said elements having ignitable portions spaced inwardly from the free ends of said elements, a striking surface spaced from the end portion the strip being folded upon itself in such manner that the ignitable portions are toward the closed end of the fold, and the striking surface is adjacent an open end of the fold whereby the removal of a match element from the folded booklet causes the ignitable portion to pass across the striking surface, the portion of the strip intermediate the striking surface and match elements supporting the detachable elements in the fold.

2. A match booklet comprising an integral strip

having an end portion slitted to form a plurality of detachable match elements and stub portions each separately connected to a match element, a weakened zone between the match elements and the stub portions, said elements having ignitable portions spaced inwardly from the free ends of said elements, the strip being folded upon itself in such manner that the ignitable portions are toward the closed end of the fold, and means for fastening the folds together.

3. A match booklet comprising an integral strip having an end portion slitted to form a plurality of detachable match elements, said elements having ignitable portions spaced inwardly from the free ends of said elements, the strip being folded upon itself in such manner that the ignitable portions are toward the closed end of the fold, the strip having a striking surface thereon adjacent an open end of the fold whereby the removal of a match element from the folded booklet causes the ignitable portion to pass across the striking surface, and means for fastening the folds together.

4. A match booklet comprising an integral strip having an end portion slitted to form a plurality of detachable match elements, and a stub portion frangibly attached to each match element and integral with the strip, said elements having ignitable portions spaced inwardly from the free ends of said elements, the strip being folded upon itself in such manner that the ignitable portions are toward the closed end of the fold, the strips having a striking surface thereon adjacent an open end of the fold whereby the removal of a match element from the folded booklet causes the ignitable portion to pass across the striking surface and moves the attached stub portion to a position where it will close off at least a part of the space vacated by the withdrawn match element.

5. A match booklet comprising an integral strip having an end portion slitted to form a plurality of detachable match elements and attached stub portions, a weakened zone dividing the match elements and the stub portions, said elements having ignitable portions spaced inwardly from the free ends of said elements and outwardly of the weakened zone, the strip being folded upon itself in such manner that the ignitable portions are toward the closed end of the fold, said match elements having a reduced cross section at the ignitable portions.

6. A match booklet comprising an integral strip having an end portion slitted to form a plurality of detachable match elements and attached stub portions, a weakened zone dividing the match elements and the stub portions, said elements having ignitable portions spaced inwardly from the free ends of said elements and outwardly of the weakened zone, the strip being folded upon itself in such manner that the ignitable portions are toward the closed end of the fold, said match elements having a reduced cross section at the ignitable portions and full cross sectional area on both sides adjacent the ignitable portions.

7. A match booklet having an open end and a closed end made from a band of pliable inflammable material, comprising two cover sections, an inwardly folded inner flap section, a match section integral with the flap section, slits extending from the interior of the flap section and through the match section to divide the material into strips, a tear line extending across the strips in the match section and frangibly dividing each

strip into a match and a stub attached to the flap, and ignitable material secured to the match adjacent the tear line.

8. A match booklet having an open end and a closed end made from a band of pliable inflammable material, comprising two cover sections, an inwardly folded inner flap section, a match section integral with the flap section, slits extending from the interior of the flap section and through the match section to divide the material into strips, a tear line extending across the strips in the match section and frangibly dividing each strip into a match and a stub attached to the flap, ignitable material secured to the match adjacent the tear line, and an area of igniting composition on the flap section, distant from the match section and so located as to be engaged by the ignitable material when the match has been substantially withdrawn from the booklet.

9. A match booklet having an open end and a closed end made from a band of pliable inflammable material, comprising two cover sections, an inwardly folded inner flap section, a match section integral with the flap section, slits extending from the interior of the flap section and through the match section to divide the material into strips, a tear line extending across the strips in the match section and frangibly dividing each strip into a match and a stub attached to the flap, ignitable material secured to the match adjacent the tear line, and an area of igniting composition on the flap section, distant from the match section and so located as to be engaged by the ignitable material when the match has been substantially withdrawn from the booklet, the length of the match and the stub being such that when the match is withdrawn from the booklet the stub will be drawn into the space vacated by the withdrawn match.

10. A match booklet having an open end and a closed end made from a band of pliable inflammable material, comprising two cover sections, an inwardly folded inner flap section, a match section integral with the flap section, slits extending from the interior of the flap section and through the match section to divide the material into strips, a tear line extending across the strips in the match section and frangibly dividing each strip into a match and a stub attached to the flap, ignitable material secured to the match adjacent the tear line, and an area of igniting composition on the flap section, distant from the match section and so located as to be engaged by the ignitable material when the match has been substantially withdrawn from the booklet, and means to secure the sections in face to face position.

11. A match booklet having an open end and a closed end made from a band of pliable inflammable material, comprising two cover sections, an inwardly folded inner flap section, a match section integral with the flap section, slits extending from the interior of the flap section and through the match section to divide the material into match strips and at least one tab, the match strips being frangibly divided into match elements and stubs, the stubs being integral with the flap section, ignitable material on each match element adjacent the stub, an igniting surface on the flap section to engage the ignitable material when the match has been substantially withdrawn from the booklet, and means passing through the cover sections and a

tab to secure the sections in face to face relationship.

12. A match booklet made from a strip of pliable inflammable material, divided transversely into sections arranged end to end, comprising two adjoining cover sections, an inwardly folded inner flap adjoining one cover section, a match section adjoining the inner flap and projecting when folded beyond the line of juncture of the one cover section and the inner flap, the other cover section being folded over the exposed match ends and overlapping the said line of juncture, the said match section and an adjoining portion of the inner flap being slit into match strips, each match strip having a tear line which divides the strip into a match and a stub, the stub being secured to the inner flap, said matches having an ignitable material disposed thereon near the tear line.

13. A match booklet having an open end and a closed end made from a band of pliable inflammable material, comprising two cover sections, an inwardly folded inner flap section, a match section integral with the flap section, slits extending from the interior of the flap section and through the match section to divide the material into strips, a tear line extending across the strips in the match section and frangibly dividing each strip into a match and a stub attached to the flap, ignitable material secured to the match adjacent the tear line, and an area of igniting composition on the flap section, dis-

tant from the match section and so located as to be engaged by the ignitable material when the match has been substantially withdrawn from the booklet, at least one of said cover sections having a portion which extends beyond the open end of the booklet.

14. A match booklet including an integral band having an end portion slotted to form a plurality of continuous parallel strips, a tear line extending transversely across the slotted end portion frangibly dividing each strip into a stub portion attached to the body of the band and a match element attached to the stub portion, each of said match elements having an ignitable portion adjacent the tear line.

15. A match booklet wherein individual match elements are withdrawn between folds on which are formed striking surfaces, comprising a band having a longitudinally slotted end portion forming a plurality of individual strips attached at one end to the band, said strips being weakened intermediate the ends thereof to form a tear line, each strip having ignitable material thereon between its free end and the weakened zone and forming a match element, the remainder of each strip between the weakened zone and the juncture of the strip with the band comprising a stub which is adapted to be moved upon withdrawal of a single match element into the space previously occupied by the removed match element.

WILLIAM LANG.
